METHOD OF MANUFACTURING SHOES

Ralph C. Simmons, Beverly, Mass., assignor to
United Shoe Machinery Corporation, Paterson,
N. J., a corporation of New Jersey

Application March 21, 1932, Serial No. 600,251

12 Claims. (Cl. 12—103)

This invention relates to improvements in methods of manufacturing shoes and is illustrated herein with respect to the manufacture of welted shoes having cement-attached soles.

5 When cement-attaching outsoles to welted shoes difficulties are encountered, particularly if the sole is to have any substantial extension beyond the shoe upper, by reason of the tendency of the sole attaching pressure to force the marginal portion of the sole and the welt toward the shoe upper thus producing a rolled-edge effect and at times endangering the security of the cement bond by which the sole is attached to the welt. It is an object of my invention to 10 provide an improved method and device by use of which the rolling of the marginal portion of the sole and of the welt toward the shoe upper will be obviated even though the sole and the welt extend a substantial distance beyond the 15 shoe upper. With this in view, I propose to insert in the crease between the welt and the shoe upper a filler piece comprising a strip of firm and flexible material, substantially non-resilient in the sense that it will retain the shape into 20 which it is bent. This strip is preferably substantially triangular in cross section, with the apex of the triangle pointing inwardly toward the inseam of the shoe, thereby supporting the welt against the sole attaching pressure.

25 With the above and other objects in view, the invention will now be described in connection with the accompanying drawing and pointed out in the claims.

In the drawing,

30 Fig. 1 is a perspective view illustrating the practice of my novel method;

Fig. 2 is a detail sectional view illustrating the manner in which the welt supporting strip is forced into the welt crease of the shoe;

35 Fig. 3 is a cross-sectional view showing the shoe during the application of the sole-attaching pressure;

Fig. 4 is a section through the inseam and adjacent parts of a shoe after the sole has been 40 attached but before the welt supporting strip has been removed; and

Figs. 5 and 6 are detail views of two forms of 45 welt supporting strips.

In the practice of my invention the shoe, illustrated at 8 in Fig. 1, may be assembled, pulled over, lasted, welted, and inseam trimmed in any suitable manner, for example as disclosed in an application for Letters Patent of the United States Serial No. 580,781, filed December 14, 1931, 50 in the name of D. W. Bunker. The inseam may

be rolled, the bottom filled, and the welt coated with pyroxylin cement also as disclosed in that application. After the cement on the welt 12 has dried but before the sole is attached, a welt crease filler piece comprising a supporting strip, illustrated at 10 in Fig. 1, is inserted in the welt-crease, that is between the welt 12 and the upper 14 of the shoe. The strip 10 should be of flexible but substantially non-resilient material and is preferably substantially triangular in cross section. As illustrated in Figs. 1, 2 and 3, the strip 10 is of rubber and is provided with a core 16 of, for example, lead or a lead alloy which is sufficiently firm and non-resilient to cause the strip 10 to retain any form to which it is bent. An 55 end portion of the strip 10 is inserted manually in the crease between the welt and the upper at the end of the welt and a tack 18 is driven through the strip into the shoe, for example by means of a tack-inserting machine 20 as suggested in Fig. 1. The shoe is then moved toward a roll 22, preferably carried by a stationary support 24 which may be mounted upon the frame of the tack-inserting machine 20, and the shoe 8 60 is moved peripherally relatively to the roll 22 to 65 force the strip 10 into the welt crease, first along one side of the shoe, then at the toe, and then rearwardly to the end of the welt at the other side of the shoe. As illustrated, and in order to 70 reduce the care which the operator need use to 75 maintain the roll 22 and the strip 10 in proper engagement, the roll is provided at its edges with a pair of shallow flanges 26 as best shown in Fig. 2. After the strip has been forced into the welt 80 crease in this fashion, its other end may be se- 85 cured, if desired, by a second tack.

With the welt supported in this fashion, the sole 28 is cement attached. The sole is prepared in the usual way, its marginal portion being roughened at its attaching surface and then given 90 a coat of pyroxylin cement. Immediately before the attachment of the sole, the cement on the welt and the adjacent part of the shoe bottom or on the sole or both is activated with a suitable softener and the sole is applied to the shoe 95 bottom, the shoe and sole being placed under pressure, for example in a cement sole attaching machine of the type disclosed in an application for Letters Patent of the United States Serial No. 388,739, filed August 27, 1929, in the name 100 of Milton H. Ballard. The pressure applying pad of such a machine is illustrated at 30 in Fig. 3. It will be observed that, as shown in Fig. 3, the strip 10 prevents the welt 12 from being rolled 105 upwardly toward or into engagement with the 110

shoe upper 14 so that the sole attaching pressure is maintained to the edge of the sole and welt even though the sole and welt extend considerably beyond the shoe upper. After the 5 shoe has been removed from the sole attaching machine the strip 10 is removed from the shoe, and may be used again and again.

It is not essential that the work supporting strip consist of rubber with a metal core as illustrated in Figs. 1, 2 and 3. Alternatively, it 10 may be formed of a strip of firm and flexible but substantially non-resilient metal, such as lead or lead alloy, and such a strip is illustrated in Figs. 4, 5 and 6. The strip illustrated in Figs. 15 4 and 5 is provided at its upper engaging surface and also at its welt engaging surface with a shoulder 32 running lengthwise of the strip and providing a recess or depression 34 back of the shoulder 32 into which the material of 20 the upper end of the welt sinks under the sole attaching pressure, thereby obviating the possibility of the strip slipping and moving transversely of itself out of the welt crease. Similarly, the strip in Fig. 6 is provided with 25 depressions 36 the walls of which form shoulders extending lengthwise of the strip, which depressions receive the shoe upper and welt under the sole attaching pressure in the same way and with the same result. It is obvious that it is not 30 necessary, in order to obtain the benefit of these shoulders and depressions, that they be formed in both the shoe upper and the welt engaging surface of the strip, for a substantial part, at least, of their benefit will be obtained if they are 35 formed in only one of these surfaces.

Having thus described my invention what I claim as new and desire to secure by Letters Patent of the United States is:

1. That improvement in methods of manufacturing welted shoes which comprises inserting a portion of a welt-supporting strip in the crease 40 between the welt and the upper of a welted shoe to which the sole has not yet been attached, bringing the portion of the strip which has been 45 inserted in the crease into engagement with the edge of a roll, and causing relative movement of the shoe and the roll peripherally of the shoe while pressing the shoe forcibly toward and the strip forcibly against the roll to work the strip 50 into the crease between the welt and the shoe upper.

2. That improvement in methods of manufacturing welted shoes which comprises inserting an 55 end portion of a temporary welt-supporting strip between the welt and the upper of a welted shoe to which the sole has not yet been attached, driving a fastening through the strip and into the shoe to serve as a temporary securing means for the strip, bringing the strip adjacent to the 60 fastening into engagement with the edge of a roll, and causing relative movement of the shoe and the roll peripherally of the shoe while pressing the shoe and the strip forcibly against the roll to work the strip into the crease between 65 the welt and the shoe upper.

3. That improvement in methods of manufacturing welted shoes which comprises inserting an 70 end portion of a temporary welt supporting strip at one end of the crease between the welt and the upper of a welted shoe to which the sole has not yet been attached, driving a fastening through the strip and into the shoe to serve 75 as a temporary securing means for the strip, bringing the strip adjacent to the tack into engagement with the edge of a roll, and causing rel-

ative movement of the shoe and the roll peripherally of the shoe while pressing the strip and the roll forcibly against each other to work the strip into the crease between the welt and the shoe upper.

4. That improvement in methods of manufacturing welted shoes which comprises inserting an end portion of a strip of material substantially triangular in cross section at one end of the crease between the welt and the upper of a welted shoe 80 to which the sole has not yet been attached, driving a fastening through the end portion of the strip and into the shoe adjacent to an end of the welt to serve as a temporary securing means for the strip, bringing the portion of the strip adjacent to the tack into engagement with the edge of a roll carried by a stationary support, and moving the shoe peripherally while pressing the strip forcibly against the roll to work the strip into the crease between the welt and the upper from the heel breast line forwardly about the toe of the shoe and then rearwardly to the heel breast line on the other side.

5. A welt crease filler piece for supporting the 85 welt of a shoe against sole attaching pressure, comprising a strip of firm and flexible material having substantially the non-resilient nature of lead, said strip being substantially triangular in cross section.

6. A welt crease filler piece for supporting the 90 welt of a shoe against sole attaching pressure, comprising a strip of firm material substantially triangular in cross section and provided with a core of flexible but substantially non-resilient material.

7. A welt crease filler piece for supporting the 95 welt of a shoe against sole attaching pressure, comprising a strip of rubber substantially triangular in cross section and provided with a core of flexible but substantially non-resilient material, said strip being adapted to be inserted with its apex in the crease between the shoe upper and the welt.

8. A welt crease filler piece for supporting the 100 welt of a shoe against sole attaching pressure, comprising a strip of rubber substantially triangular in cross section and provided with a lead core, said strip being adapted to be inserted with its apex in the crease between the shoe upper and the welt.

9. A welt crease filler piece for supporting the 105 welt of a shoe against sole attaching pressure, comprising a strip of firm and flexible but substantially non-resilient material substantially triangular in cross-section and provided with a 110 lengthwise extending depression into which the substance of the material of the shoe may be forced by the sole attaching pressure, thereby anchoring the strip against transverse movement away from the shoe.

10. A welt crease filler piece for supporting the 115 welt of a shoe against sole attaching pressure, comprising a strip of firm and flexible but substantially non-resilient material substantially triangular in cross section and provided with a 120 shoulder extending lengthwise of the strip and a depression back of the shoulder into which the substance of the shoe upper material may be forced by the sole attaching pressure, thereby anchoring the strip against transverse movement 125 away from the shoe.

11. A removable flexible metal welt strip filler 130 piece shaped to fit into the crease between the outer edges of a shoe bottom and the shoe upper and of such length and flexibility as to be capable 135

of being bent around the toe from one side of the sole to the other.

12. A filler strip for supporting the outer edge of a shoe bottom against a form-supported shoe upper, for use in clamping and adhesively securing a sole to said upper, said strip being composed of material pliable enough to permit it to be

bent into conformity to said bottom and upper, around the sides and toe of the shoe, by manipulation with the fingers, but having inherently the necessary non-resiliency, rigidity and compressive strength to maintain itself in the supporting relation when so conformed. 80

CERTIFICATE OF CORRECTION.

Patent No. 1,951,493.

March 20, 1934.

RALPH C. SIMMONS.

It is hereby certified that error appears in the printed specification of the above numbered patent requiring correction as follows: Page 2, line 20, for "upper end" read shoe upper and; and that the said Letters Patent should be read with this correction therein that the same may conform to the record of the case in the Patent Office.

Signed and sealed this 19th day of June, A. D. 1934.

Bryan M. Battey
